(57)

CLAIM

The ornamental design for a pressure washer, as shown and described.

DESCRIPTION

FIG. 1 shows a front perspective view of a pressure washer showing the new design.

FIG. 2 is a rear perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof; and,

FIG. 8 is a bottom view thereof.

The broken lines shown in the figures are for the purpose of illustrating portions of the pressure washer and form no part of the claimed design.

1 Claim, 8 Drawing Sheets(56)
